UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,369,488.

Specification of Letters Patent. Patented Feb. 22, 1921.

Application filed January 30, 1920. Serial No. 355,067.

To all whom it may concern:

Be it known that I, MELVIN L. STONE, a citizen of the United States, and a resident of Lawrence, county of Essex, and State of 5 Massachusetts, have invented an Improvement in Feeler Mechanisms for Looms, of which the following description, in connection with the accompanying drawings, is a specification, like characters on the drawings 10 representing like parts.

This invention relates to feeler mechanisms for looms whereby the operative condition of a loom is changed prior to complete exhaustion of the filling in the running 15 shuttle.

The object of the present invention is to provide a feeler mechanism which shall be simple in construction, sensitive to the presence or substantial absence of filling in the 20 shuttle, and which shall be reliable and effective in operation and call the change when a minimum amount of filling remains on the filling carrier or bobbin.

The present feeler mechanism relates more 25 particularly to that type wherein the feeler member is displaced or moved laterally by the forward pressure upon it when, on a detecting beat, the filling has become substantially exhausted. In carrying the invention into practical effect, the detecting 30 element is preferably formed of two feeler members which are pivotally mounted for movement toward and from each other in a direction longitudinally of the shuttle and 35 which carry laterally movable shoes which act upon an actuator and position it for effecting replenishment of filling when the feeler members have been moved longitudinally of the shuttle on a detecting beat due 40 to forward pressure thereagainst when the filling is substantially exhausted.

In the drawings:

Figure 1 represents a perspective view of the detecting side of a loom with the present 45 invention associated therewith, some of the parts being omitted for clearness of illustration;

Fig. 2 is an enlarged detail plan view showing more particularly the relation of parts when a working supply of filling is 50 present in the shuttle on a detecting beat;

Fig. 3 is a view similar to that of Fig. 2 but showing the relation of parts when filling is substantially exhausted on a detecting 55 beat;

Fig. 4 is a section on the line 4—4 of Fig. 3; and

Fig. 5 is a longitudinal section of the feeler mechanism.

The loom frame 1 has secured thereto the 60 brackets 2, one at each side of the loom in which is supported the transverse or rock shaft 3 having the arm 4 rising therefrom to which is pivoted at 5 the latch 6. The rear end portion 7 of the latch 6 is adapted at 65 times to be engaged by an operating member 8 which may be either a weft hammer, or a part connected thereto, the construction being such that when the end 7 of the latch is engaged by the operating member 8, as it 70 moves forwardly, the rock shaft 3 will be turned to effect replenishment of filling, as is common and well-known in this type of looms.

Pivotedly mounted on the loom frame or 75 a bracket 9 rising therefrom, is the transmitter 10, one end 11 of which is associated with the latch 6 and the other end of which carries the usual cam portion 12. Pivotedly mounted at 13 is the controller 14 which 80 passes above the end portion 12 of the transmitter and is normally held in its rearward position, as indicated in Fig. 1, by a spring 15. The parts so far described may be like 85 or similar to corresponding parts in the well-known Draper feeler as shown by the patent to Wood & Northrop No. 789,471, May 9, 1905.

Extending from the shipper stand 16 is a slotted bracket 17 to which the feeler stand 90 18 may be adjustably secured as by the bolt 19. The feeler stand is of the usual character or may be such as disclosed in the patent above referred to.

Mounted for movement toward and from 95 the front of the loom in the feeler stand 18, is the feeler carrier or slide 20 which has a shouldered portion 21 between which and the front portion of the feeler stand 18 is interposed a spring 22 normally acting to hold 100 the feeler carrier or slide 20 in its rearward position.

Pivotedly mounted on the feeler carrier or slide 20 is the actuator 23 which, in the present instance, is pivoted at 24 upon the 105 up-standing lugs 25 rising from the feeler carrier or slide. The actuator 23 is normally under the influence of a pin 25 which is impelled upwardly by a spring 26, thereby normally maintaining the actuator 23 with 110

its end 27 in position above the controller 14, as indicated in Fig. 1, the construction being such that if at such times the feeler carrier or slide 20 is moved frontwardly of 5 the loom, the path of movement of the end 27 of the actuator will pass above the controller 14 which will, therefore, not be moved by the actuator.

The feeler carrier or slide 20 extends rear- 10 wardly beyond the pivotal mounting of the actuator 23 and to the rear portion 28 thereof are pivoted at 29 the feeler members 30 each of which has its rearwardly extending end 31 turned divergently outwardly.

15 The two feeler members 30 are connected by a spring 32 which normally tends to hold the feeler members 30 with their forward end portions resting against the stops 33 which project from the feeler carrier or 20 slide.

To the front end portion of each of the feeler members 30 is connected a shoe which, when the feeler members are moved relatively in a direction longitudinally of the 25 shuttle, will be moved transversely of the feeler carrier 20.

These shoes may be variously contrived, but in the present instance one of the shoes 34 which is pivotally connected to its feeler 30 member 30 by the pivot 35, has a general wedge shape, as best indicated in Fig. 4; that is to say, it is widest adjacent the pivot 35 and tapers toward its free end. The other shoe 36 is pivotally connected to the 35 other feeler member at 37 and has its end portion 38 upwardly curved somewhat, the construction being such that when the shoes are moved toward each other into overlapping relation, as indicated in Figs. 3 and 4, 40 the end 38 of the shoe 36 will direct the toe end portion of the shoe upwardly over the inclined surface of its companion shoe.

The actuator 23 has extending rearwardly from its pivotal support 24, a ledge or plate 45 39 normally in a position over the shoes 34 and 36, the construction being such that when, on a detecting beat, a working supply of filling is present in the shuttle, and the feeler members remain relatively undis- 50 turbed, as indicated in Fig. 2, on a detecting beat, the ledge 39 will rest upon the top surface of the shoes, or one of them, and the actuator will remain inoperatively positioned relative to the controller 14 as the 55 lay beats up. Should, however, the filling be substantially exhausted on a detecting beat, the feeler members 30 will be separated at their rear end portions, as indicated in Fig. 3, and the shoes 34 and 36 will ride over 60 each other or overlap and the shoe will raise the ledge 39, thereby causing the actuator 23 to be depressed into position to engage the controller 14 upon further front- 65 ward movement of the lay to thereby effect replenishment of filling.

If a single feeler member 30 were employed instead of the two feeler members as described and which constitutes the preferred form of the invention, the connected shoe, moving under the ledge 39 as the feeler member is moved longitudinally of the shuttle, on a detecting beat, would operatively position the actuator for replenishment of filling.

The lay 40 may be of usual construction 75 and have the shuttle box 41 into which is received the shuttle 42 carrying the bobbin 43. The front wall of the shuttle box is slotted at 44 and so also is the adjacent wall 45 of the shuttle, the construction being 80 such that when the shuttle is properly boxed, the openings through the front wall of the shuttle box and adjacent wall of the shuttle will register to permit the entrance of the feeler members on a detecting beat. 85

Claims:

1. In a feeler mechanism for looms, the combination of two feeler members mounted for movement in opposite directions longitudinally of the shuttle and held from such movement by engagement with the filling on a detecting beat until substantial exhaustion thereof, an actuator pivotally mounted to swing in a substantially vertical plane, and lifting shoes connected to the feeler 95 members to swing the actuator into position for effecting replenishment of filling when the shoes are moved transversely into overlapping position.

2. In a feeler mechanism for looms, the combination of two feeler members mounted for movement in opposite directions longitudinally of the shuttle and held from such movement by engagement with the filling on a detecting beat until substantial exhaustion thereof, shoes pivotally connected to the feeler members and movable to an overlapping position when the feeler members are moved longitudinally of the shuttle on a detecting beat, and an actuator operatively positioned by the shoes to effect replenishment of filling. 105

3. In a feeler mechanism for looms, the combination of a feeler carrier, two feeler members pivotally mounted on the carrier 110 for movement in opposite directions by the forward push against them when the filling is substantially exhausted on a detecting beat, shoes connected to the feeler members to ride one over the other when the feeler members are moved in opposite directions by the forward push on a detecting beat, and an actuator positioned by the shoes for effecting replenishment of filling. 115

4. In a feeler mechanism for looms, the combination of a feeler carrier, two feeler members pivotally mounted on the carrier 120 for relative movement longitudinally of the shuttle when the filling is substantially exhausted on a detecting beat, a spring con- 125 130

necting the two feeler members and normally opposing their relative movement longitudinally of the shuttle, a shoe movable laterally of the carrier by the feeler members when the feeler members are relatively moved longitudinally of the shuttle on a detecting beat, and an actuator mounted on the carrier and having a rearward extension which is moved in a substantially vertical direction by the shoe to cause the actuator to effect replenishment of filling when the shoe is moved laterally of the carrier.

5. In a feeler mechanism for looms, the combination of a feeler carrier, a feeler member mounted on the carrier for movement longitudinally of the shuttle by the frontward push upon it when the filling is substantially exhausted on a detecting beat, a shoe connected to the feeler member and moved laterally of the feeler carrier by the feeler member when the latter is moved longitudinally by the frontward push, and an actuator which is also mounted on the feeler carrier and has a rearward extension overlying the shoe and by which the actuator is operatively positioned by the shoe as it moves laterally of the feeler carrier to effect replenishment of filling.

10. 6. In a feeler mechanism for looms, the combination of a feeler carrier, two feeler members mounted on the carrier for relative movement longitudinally of the shuttle by the frontward push when the filling is substantially exhausted on a detecting beat, a shoe pivotally connected to one of the feeler members and moved laterally of the feeler carrier when the feeler members are relatively moved longitudinally of the shuttle by the frontward push, and an actuator

which is operatively positioned by the shoe as it moves laterally of the feeler carrier to effect replenishment of filling.

7. In a feeler mechanism for looms, the combination of a feeler carrier, two feeler members pivotally mounted on the carrier, a spring acting to hold the front end portions of the feeler members in separated relation, a shoe pivotally connected to the front end portion of each of the feeler members and adapted to ride one over the other, and an actuator positioned by the shoe as they ride one over the other to effect replenishment of filling.

8. In a feeler mechanism for looms, the combination of a feeler carrier that is moved frontwardly on each detecting beat, an actuator mounted on and movable with the feeler carrier and having a rearwardly extending ledge, a feeler member also pivotally mounted on the same feeler carrier for lateral displacement, and a shoe connected to the feeler member for lateral movement therewith beneath the ledge of the actuator to operatively position the actuator when filling is substantially exhausted on a detecting beat.

9. A feeler mechanism for looms, comprising, in combination, a feeler carrier, an actuator mounted on the carrier, two feeler members pivotally mounted on the feeler carrier and each having a pivoted shoe, said shoes being shaped to ride one over the other and operatively position the actuator when filling is substantially exhausted on a detecting beat.

In testimony whereof I have signed my name to this specification.

MELVIN L. STONE.
